Patented June 27, 1922.

UNITED STATES PATENT OFFICE

BERNARD F. FEHLMAN, OF DENVER, COLORADO.

UNDERREAMER.

1,420,918.

Specification of Letters Patent. Patented June 27, 1922.

Application filed June 27, 1921. Serial No. 480,819.

To all whom it may concern:

Be it known that I, BERNARD F. FEHLMAN, a citizen of the United States, residing at Denver, in the county of Denver and State 5 of Colorado, have invented certain new and useful Improvements in Underreamers, of which the following is a specification.

This invention relates to underreamers of the type used in the construction of wells 10 to enlarge the bore thereof beneath an inserted casing.

It is an object of the present invention to provide in a tool of the above mentioned character, a simple and effective arrangement of strong and durable operative parts. A further object is to provide readily accessible means for adjustment of the springs which act upon the outwardly projecting cutting members, and still another object is 20 to provide the cutting members of the tool with lapping shanks which cooperate to clean the members from adherent mud when moved together in the operation of the tool.

With the above and other objects in view, 25 all of which are fully brought out in the course of the following description, my improved underreamer consists of the construction and arrangement of parts shown in the accompanying drawings in the several 30 views of which like parts are similarly designated, and in which

Figure 1 represents an elevation of the improved tool in its operative position in a well bore;

35 Figure 2, a partially sectional fragmentary face view of the body section of the tool showing the two cutting members thereof in their operative position beneath the casing of a well bore;

40 Figure 3, a view similar to that of Figure 2, showing the bits tied together in the position they occupy when the tool is inserted in the casing;

Figure 4, a transverse section on the line 45 4-4, Figure 2, and

Figure 5, a similar section taken on the line 5-5, Figure 3.

Referring more specifically to the drawings, the reference character 2 designates a 50 well bore, and 3 the protective casing thereof. The tool of my invention comprises a bit carrying stock 4 which as usual is attached at the lower end of a drill stem through the medium of a shank 5. The 55 stock is composed of a body section 6 and a

cap section 7 which adjoin each other in an axial plane and are detachably fastened together by means of transverse screws, pins or bolts 8.

The contiguous faces of the two stock sections are hollowed to provide seats 9 for the semi-spherical knuckles 10 of the bits hereinafter to be described, and in connection therewith, guide ways 12 for headed push bars 13 which engage in peripheral notches 10° of the knuckles, and continuous with said ways, chambers 14 for coiled springs 15 which act upon the push bars.

The axially aligned guide ways and spring chambers slant toward the peripheral surface of the stock section in which they are formed and the chambers have at their ends threaded openings for adjusting screws 16 which engage with abutment blocks 17 inserted in the upper end portions of the 75 springs. The headed ends of the adjusting screws extend in recesses 18 of the exterior surface of the stock where they are readily accessible for the application of a wrench, screw driver or other suitable tool. 80

The bits or cutting members of the underreamer projecting beyond the lower end of its stock, each consist of a cutting head 19 provided with a rounded cutting edge and formed integrally at the end of a flat-faced 85 shank 20 which terminates in the semi-spherical knuckle hereinbefore referred to. The knuckles of the two cutting members are conjointly fitted in the correspondingly shaped cavities of the stock formed by the 90 seats 9 of its stock sections and they are further held against displacement by a pivot pin 21 which extends centrally through bores in the knuckles and therewith aligned openings in the wall of the stock. 95

The flat shanks of the bits lie in lapping relation to each other so that when the bits are moved together they will shear away the dirt which in the operation of the tool has lodged between the cutting members. The 100 removal of this dirt is of particular value in the operation of a tool of this character since its presence greatly interferes with the withdrawal of the tool through the well casing.

In the use of my improved tool the bits are tied together by a fragile band 22 or other convenient means as shown in Figure 3 of the drawings, to permit of its insertion through the casing which in wells of great 110

depth are employed to secure against the caving of their walls.

After the bits are closed together the springs are tensioned by means of the adjusting screws and the tool in this condition is lowered in the well until the cutting members reach the space produced beneath the casing after the latter has been slightly raised, when by rotation of the tool the 10 fragile band which held the bits together is broken and the bits are forcibly pressed against the wall of the bore under the influence of their respective springs.

The outward movement of the cutting 15 members is limited by the engagement of shoulders formed at the juncture of their exteriorly sloping cutting heads and their shanks, with the end of the stock and the continued rotation of the tool and simultaneous 20 downward feed of the same will cause the bits to ream the ground beneath the casing to a diameter corresponding with the distance between their curved cutting edges.

25 The displaced earth is constantly removed from the well bore by means ordinarily employed for this purpose and after the work is completed the tool is readily removed from the well by an upward pull which 30 causes the normally diverging heads to close together by engagement of their sloping outer surfaces with the end of the casing.

Having thus described my invention what I claim and desire to secure by Letters- 35 Patent is:

1. An under reamer comprising a stock having a spherical seat, outwardly projecting bits having semi-spherical knuckles conjointly fitting in said seat, and spring- 40 pressed means to yieldingly maintain the bits in their projecting position.

2. An under reamer comprising a stock having a spherical seat, outwardly projecting bits having semi-spherical knuckles conjointly fitting in said seat, a pivot pin passing centrally through the knuckles, and spring-pressed means to yieldingly maintain the bits in their projecting position. 45

3. An under reamer comprising a stock 50 having a knuckle-seat, outwardly projecting bits having cutting heads exteriorly of the stock, knuckles conjointly fitted in said seat and flat-faced shanks between their knuckles and their heads, the faces of said shanks 55 lapping in shearing relation to each other, and spring-pressed means to yieldingly

maintain the bits in their projecting position.

4. An under reamer comprising an exteriorly recessed stock having an interior 60 knuckle-bearing, outwardly projecting bits having knuckles conjointly fitted in said bearing, push-bars engaging with the knuckles, springs pressing on said push-bars, and adjusting-screws acting upon the 65 springs and extending partially into the exterior recesses of the stock.

5. An under reamer comprising a stock composed of sections adjoining in a longitudinal plane and each having a circular 70 seat, an outwardly slanting guide way connected therewith, a spring chamber continuous to the guide-way, and an exterior recess divided from the chamber by an apertured wall, bits having cutting heads projecting 75 outwardly from the stock and knuckles rotatably fitted in the seats of the same, push-bars in the guide ways, engaging with the knuckles, springs in the chambers pressing on the push-bars, and adjusting screws in 80 the recesses, extending into the chambers and acting upon the springs.

6. An under reamer comprising a stock composed of sections adjoining in a longitudinal plane and each having a semi- 85 spherical seat, a guide way connected therewith and a spring-chamber continuous to the guide way, outwardly projecting bits having notched semi-spherical knuckles in said seats, push-bars in the guide ways, engaging in the notches of the knuckles, and springs in the chambers, acting upon the push bars. 90

7. An under reamer comprising an exteriorly recessed stock having a knuckle seat, 95 outwardly projecting bits having knuckles in said seat, spring-pressed means acting upon the knuckles to yieldingly maintain the bits in their projecting position, and adjusting screws in the exterior recesses of the 100 stock, acting upon said means.

8. An under reamer comprising a stock having a knuckle seat, outwardly projecting bits having knuckles in said seat, spring-pressed means acting upon the knuckles to 105 yieldingly maintain the bits in their projecting position, and adjusting screws exteriorly of the stock, acting upon said means.

In testimony whereof I have affixed my 110 signature.

BERNARD F. FEHLMAN.
